[57] CLAIM

The ornamental design for a shield for an aerosol dispensing device, as shown and described.

DESCRIPTION

FIG. 1 is a front elevation view of a shield for an aerosol dispensing device according to the present invention.

FIG. 2 is a right side elevation view of the shield shown in FIG. 1.

FIG. 3 is a left side elevation view of the shield shown in FIG. 1.

FIG. 4 is a rear elevation view of the shield shown in FIG. 1.

FIG. 5 is a top plan view of the shield shown in FIG. 1.

FIG. 6 is a bottom plan view of the shield shown in FIG. 1; and,

FIG. 7 is an isometric view of the shield shown in FIG. 1.
